FUEL-FEEDING APPARATUS

Application filed March 5, 1925. Serial No. 13,223.

This invention relates to fuel feeding apparatus or so called "vacuum tanks" which have become almost universally employed in motor vehicles for raising fuel from a low level supply tank and distributing it to the carburetor of the engine.

It is, in effect, a pumping device, using a sub-atmospheric pressure for giving the required lift for raising the fuel. This sub-atmospheric condition may be secured in various manners, either from the oil pumping system; from the inlet of the manifold or from attachment to the exhaust.

The device herein specifically defined relates to a special form and type of device having certain features of advantage hereinafter set forth.

The main object of the invention is to provide simple, compact and effective features of the character described, which can be made in condensed or enlarged form.

A further object is to insure proper opening and closing of the valves in the mechanism.

25 Referring to the drawings:

Fig. 1, is a vertical section of the device.

Fig. 2, is a top plan view illustrating its attachment to a support.

Fig. 3, is a similar view in side elevation, 30 partially broken in section to show the inner operating chamber.

Fig. 4, is a plan view of the bottom of the operating chamber.

Fig. 5, is a fragmentary view showing a 35 modified arrangement of receptacles and priming conduit.

Fig. 6, is a similar plan view.

Fig. 7, is a fragmentary view of the bottom plate and connections.

40 In all devices of this character, certain relations must be provided for and maintained so that the device will operate on low suction or high suction.

Difficulties have been experienced in arranging the various valves and controls to 45 give rapid operation for pumping the charges of fuel drawn up to the operating chambers.

The present invention is designed to eliminate faults of this character, as far as possi-

ble, and to provide a very compact float and valve mechanism which will operate with great certainty.

In the accompanying drawings, A, indicates the outer casing which is here shown as 55 of rectangular form.

A "working chamber" is arranged within an interior casing B, also of rectangular form, but not completely filling the casing A. It has a close slip fit with three sides of the 60 casing A, and is supported on the upper edge of the said casing. Along one side there is a space C, between the inner and outer casings and the inner casing is held in place by a spring D. A hinged cover E, closes the 65 opening between the two cases and offers a convenient and comparatively large space, for priming features, when necessary.

The apparent ease with which the inner casing and appurtenant parts, connected 70 with the working chamber, may be removed from the main casing is obvious.

The lower portion of the casing A, provides what may be termed a distributing chamber 75 a. This communicates through a conduit 1, with the carburetor. The inner casing B, has a connecting block 2, at its upper end, said block being secured thereto by a tubular threaded nipple 3, which serves to connect the interior of the operating chamber so with a fuel supply connection 4.

The block 2, is further secured by a tubular threaded member 5, the interior of which connects with a suction opening 6.

Tubular member 5, extends into the operating chamber and has, at its upper end, a valve seat 7, controlled by a valve 8, on the 85 end of float rod 9. This float rod is of such a diameter that a space is left between it and the bore of the member 5, as at 9, which space 90 communicates with the interior of the operating chamber through an opening 10.

A suitable float 11, is secured to the lower end of the spindle of the valve 8, and overlying the float is an inverted cup 12, secured to the member 5, by a nut 13. This cup forms an hydraulic control chamber for the float.

The float and its spindle carries a cup shaped shield 14, the upper edge of which extends above the lower edge of the inverted 100

cup 12. This arrangement of cups and ducts forms what is, in effect, a control chamber for the float and is an efficient means for aiding the float in action, giving a powerful opening and closing effect upon the valve 8, with a minimum size of float.

There is a metered atmospheric opening, as at 15, which communicates with the interior of the operating chamber. This is constantly open but does not "bleed" sufficient air into said chamber to destroy the effective operation of the vacuum in raising fuel to the working chamber.

Extending from the lower end of the working chamber is a drop tube 16, controlled by a valve 17, which, in turn, is connected with a float lever 18, and its float 19, through a suitable link 20.

Surrounding the lower end of the drop tube 16, is a chamber 21, open at the bottom as at 22. The valve 17, is somewhat larger than the end of the drop tube 16, leaving a comparatively small clearance between its peripheral edge and the interior of the chamber 21.

This arrangement is effective in taking advantage of the suction effects of the operating chamber for closing the valve 17, though not interfering with the flow of fuel from the operating chamber to the distributing chamber.

The small float 19, must have just sufficient weight, when not immersed, in the liquid, to a little more than counterbalance the valve 17, and thereby keep the latter to its seat. It must have sufficient buoyancy, however, when immersed, to open the valve 17, and keep it open, unless there is a high vacuum in the operating chamber, sufficient to bring the valve back to its seat and overcome the buoyancy of the float. The suction of the operating chamber aids in more readily closing the valve 17, against the buoyancy of the float 19, when there is partial vacuum in the operating chamber.

The lower plate 14, of the hydraulic chamber is perforated as at 14^a, so that as soon as the liquid level in the operating chamber drops below said plate 14, a pressure within the inverted cup 12, will be neutralized to that of the pressure in the operating chamber, allowing a quick discharge of any liquid in the inverted cup and a quick forceful pull of the float upon its valve rod for opening the valve 8. A hooked stem 9^a, determines the lower limit of movement of the valve 8, and appurtenant parts.

As a constructional feature of advantage, a bar of metal is formed into a rectangular reinforcement 23, thus saving the expense of punching from sheet and the consequent waste. Likewise, the lower edge of the chamber is formed up and bent over the stiffener 23, as at 24, thus giving a firm bottom to which to secure the bottom plate 25, which carries the dependant tube 16, valve, and

float mechanism. This plate is secured in place by screws 26, which makes the interior of the operating chamber accessible.

It will be quite apparent that the parts may be very readily and accurately assembled with a minimum cost and by ordinary labor, the hydraulic chamber with its float and suction valve may be assembled as "a unit" and its application to the interior of the operating chamber secures the connection block in place, after the nipple 3, has been set up. Likewise, the whole valve and float mechanism of the plate 25, may be assembled as "a unit" and applied to the bottom of the chamber.

There is thus an advantage in the rectangular form of tank structure, both as to point of economy in material and ease of manufacture and labor for ready assembly.

The bleed hole or metered opening 15, is illustrated as somewhat exaggerated, and ordinarily this is not much greater than a 60 drill, and may be less.

In the form of device herein above described, it is apparent that with the parts in the position of Figure 1, suction, being induced from any proper source, will overcome the atmospheric bleed 15, and cause fuel to be raised into the operating chamber through the connection 4, and nipple 3. The valve 17, is, of course, closed and the chamber *a*, is under atmospheric pressure.

As the liquid level rises in the operating chamber, sufficiently high to raise the float 11, the valve 8, will be seated, shutting off the suction; thereupon, the bleed hole 15, will leak enough air to neutralize high suction in the operating chamber and, as the float 19, is fully immersed, it will open the valve 17.

The flow of liquid through the drop tube 16, to the distributing chamber *a*, will hold this valve open until the liquid level has dropped in the operating chamber.

During the drop of the liquid level below the plate 14, the pressures within the inverted cup 12, and the operating chamber will be neutralized until the buoyancy of the float 11, is completely overcome and it will drop, pulling upon the valve 8, even against the suction of the suction connection 6, thereupon a suction effect will be again induced in the operating chamber.

The valve 17, will always be closed with certainty when the level drops below the buoyant point of the float 19, but if there is suddenly high suction, this will aid in closing the valve against slight buoyant action of the float 19.

Thus, the entire range of suction effects is well taken care of to secure certainty of operation of the device. It will operate on either low or high suction and its valves will clear and function in a proper manner.

From the above, it will be noted that there is an operating chamber which is closed, ex-

cept for the metered atmospheric opening 15, and fuel inlet 4, and is automatically opened and closed to the distributing chamber α , which is under atmospheric tension and to the suction connection 6, which is always under sub-atmospheric condition during the 5 operation of the device.

Should the suction entirely fail, the entire 10 contents of the operating chamber would be delivered to the distributing chamber and this always provides sufficient fuel for the carburetor for starting the engine and re-establishing sub-atmospheric conditions for pumping.

Figures 5 and 6, show a modified form of 15 slip tank arrangement where a form of tank other than that of rectangular form, as heretofore described, may be employed, and at the same time give a large area priming conduit.

20 In these figures, a cylindrical or other form of casing b , is slipped within the outer casing a , which as to the greater part of its surface, contacts with the inner casing b , the outer casing, however, is distended at some given point, as at c , to form a conduit d , which, as illustrated in the drawings, is of tapered form and is closed by a cover e .

25 While the rectangular form may be considered as preferred, the same method of securing a large priming conduit may be readily effected in cylindrical casings, as illustrated in the figures just described, and this form may be applied where fixtures are 30 already in use for manufacturing cylindrical tanks.

The general functions and operations are 35 the same, the receptacle casings slide one within the other, the inner one partially filling the outer one and leaving a space of considerable area forming a large priming duct between the casings at some one point.

40 The bottom of the main casing A , is so designed that it obviates much trouble heretofore experienced in securing tight connection for the outlet duct 1, and the cleaning valve, and provides a stiff construction which permits interchange of connections without liability of twisting and breaking.

45 This bottom plate 27, has a depression 28, formed by forcing out the material of the plate 27, and within this is secured, by soldering, a block 29, to which the outlet connection 1, and the cleaning plug 30, may be conveniently secured.

50 This block 29, forms a stiffener of sufficient thickness to be tapped out for the connections and together with the displaced metal of the plate 27, gives an extremely rigid and non-buckling structure.

55 It will be apparent that in screwing up either of the connections, there is a long leverage afforded by the block 29, to resist buckling of the bottom plate.

What I claim as my invention and desire to secure by Letters Patent is:

1. In a fuel feeding apparatus, an operating chamber having a liquid supply connection, a suction connection, a constantly open atmospheric port, a discharge connection, a controlled valve for the discharge connection, a controlling valve for the suction connection, a float and an hydraulic chamber co-operatively acting with the float for said valve.

2. In a fuel feeding apparatus, an operating chamber having a liquid supply connection, a constantly open atmospheric port, a suction connection, a valve controlled discharge connection, a balancing float for the valve controlled discharge, a controlling valve for the suction connection, a float for said valve and an hydraulic chamber co-operatively acting with the float.

3. In a fuel feeding apparatus, an operating chamber having a liquid supply connection, a constantly opened metered atmospheric port, a suction connection, a discharge connection, a balancing float and a valve controlled in part thereby for the discharge connection, a controlling valve for the suction connection, a float for said valve and an hydraulic chamber coacting with said float, the actuations of the float and valve 95 of the suction connection, collaterally co-operating with the float and valve of the discharge connection to control the operations of the operating chambers.

4. In a fuel feeding apparatus, an operating chamber having a liquid supply connection, a constantly open atmospheric port, a suction connection, a discharge connection valve and float controlled, a float controlled valve for the suction connection, a float for closing and opening the suction connection upon a rise and fall of liquid level in the chamber and means for modifying the action of the float under its normal buoyancy reactions.

5. In a fuel feeding apparatus, an operating chamber, a suction connection and a liquid supply connection, discharge connections, a valve controlling flow of fluids through the discharge and a counter balance float for the valve having variable reactions upon the valve.

6. In a fuel feeding apparatus, an operating chamber, a suction connection, a liquid supply connection, a discharge connection, a float operated valve controlling the suction of said chamber, a valve cooperating with said float operated valve and controlling flow of fluids through the discharge connection and a counter balancing float for said last named valve.

7. In a device of the character described having an operating chamber with float controlled means for intermittently drawing a supply of liquid thereinto, a discharge for

- the chamber, a valve controlling the discharge and a separate float independent controlled means operatively connected with the valve for opening and closing the latter upon variations of liquid level in the chamber.
8. In a device of the character described having an operating chamber, and a discharge port, a valve controlling said discharge port and a downwardly open chamber encircling the valve, said chamber extending above the valve and discharge port and below the same.
9. In a device of the character described having an operating chamber and a discharge port, a valve larger in diameter than the port for controlling the same and a chamber extending downwardly and surrounding the port and extending above the valve providing a restriction between the periphery of the valve and the wall of the chamber.
10. In a device of the character described, a chamber, a block for said chamber provided with a plurality of ducts, one wall of the chamber having openings, tubular nipples passing through the openings and engaging said block, clamping the block to the chamber wall, said nipples forming connecting conduits with the ducts of the block.
11. In a device of the character described, having an operating chamber, a block for exterior conduit connections, a tubular nipple clamping said block to the casing of the chamber and forming a connection thereto with one of said conduits, a tubular connection also clamping said block to the casing and forming an opening from another of said conduits to the chamber and a valve seat appurtenant to said nipple.
12. In a device of the character described, an operating chamber, a block for an exterior conduit connection, a tubular nipple clamping said block to the casing of the chamber and forming a connection thereto, a valve seat in said tubular nipple, a valve cooperating with the valve seat and having a valve stem and a float rigidly secured to the valve stem.
13. In a device of the character described, an operating chamber, a block having a conduit connection, a tubular nipple clamping said block to the casing of the chamber, a valve seat in said nipple, a valve co-operating with the seat, a float connected with the valve stem, and an inverted cup secured to the nipple and encircling the float.
14. In a device of the character described, an outer casing of rectangular form, forming a discharge container, a rectangular casing partially filling and closing the outer casing, a cover completing the closure and resilient means for holding the inner casing with reference to the outer casing.
15. In a device of the character described, an outer rectangular casing, an inner rec-
- tangular casing slipping within the outer casing and supported thereby, said casing partially filling and closing the outer casing, a priming space between one wall of the outer casing and a wall of the inner casing, and a cover for said priming space.
16. In a device of the character described, an operating chamber of rectangular form, a rectangular reenforcing frame and a rectangular opening in the bottom of the casing formed by turning up walls about the rectangular reenforcing frame.
17. In a device of the character described, an operating chamber of rectangular form, a rectangular reenforcing frame, a rectangular opening in the bottom of the casing formed by turning up walls about the rectangular reenforcing frame, and a plate secured to the rectangular reenforcing frame and forming a closure for the bottom of the chamber.
18. In a device of the character described, an outer casing forming a chamber of rectangular form, an inner casing slipping within the outer casing and having a slip fit on three sides with reference to the outer casing, providing a gap between the remaining side and the outer casing and a cap for closing said gap.
19. In a device of the character described, an operating chamber of rectangular form, a rectangular reenforcing frame, a rectangular opening in the bottom of the casing outlined by said frame and by the turned up walls about the rectangular opening and about the frame, a plate secured to the rectangular frame and forming a closure for the bottom of the chamber, said plate supporting a valve controlling mechanism for the operating chamber.
20. In a device of the character described, an operating chamber, a flat bar bent to form a reinforcement for the bottom of said chamber, an opening in the wall of said chamber formed by cutting and bending the material of the wall against the frame and a plate removably secured to the frame and forming a closure for the bottom of the chamber.
21. In a device of the character described, an operating chamber, a float controlled valve mechanism supported entirely from the head of said chamber, a removable closure for the bottom of the chamber having a discharge opening and a float controlled valve for said opening supported entirely upon the removable plate.
22. In a device of the character described, a chamber, a connection block having a duct for communication through the wall of the chamber, a tubular nipple extending from the interior of the chamber and screw threaded to engage said block and having a flange clamping the block in place, with reference to the chamber wall and forming a connecting conduit with the duct of the block.
23. In a device of the character described,

an outer casing, an inner casing slipped therein, said outer casing being enlarged at one section to provide a priming duct between the wall of the inner casing and the outer casing.

5 24. In a device of the character described, an outer casing, an inner casing slipped therein, said outer casing being enlarged at one section to provide a priming duct between the wall of the inner casing and the outer casing and a cover for said duct.
